PROTECTIVE INSTALLATION FOR ELECTRIC CIRCUITS

Filed May 9, 1922

Fig. 1.

Fig. 2.

UNITED STATES PATENT OFFICE.

CHARLES E. BENNETT, OF DECATUR, GEORGIA, ASSIGNOR TO BALT MANUFACTURING COMPANY, OF ATLANTA, GEORGIA, A CORPORATION OF GEORGIA.

PROTECTIVE INSTALLATION FOR ELECTRIC CIRCUITS.

Application filed May 9, 1922. Serial No. 559,672.

To all whom it may concern:

Be it known that I, CHARLES E. BENNETT, a citizen of the United States of America, residing at Decatur, in the county of DeKalb and State of Georgia, have invented certain new and useful Improvements in Protective Installations for Electric Circuits, of which the following is a specification.

10 My invention relates to a protective installation for electric circuits, and particularly for low voltage distribution circuits. The object of my invention is to provide an installation which will effectively protect 15 such a circuit, not only against over-potentials at low frequency, but also against high frequency potentials.

In the accompanying drawings—

20 Fig. 1 is a diagram of an illustrative installation; and

Fig. 2 is a vertical section through a more or less diagrammatically shown practical embodiment, in one form, of the protective elements of the installation.

25 In low voltage lines—say lines of from 30 to 300 volts such as are used for house wiring, signal circuits, telephone lines, etc.—there is a constant fire hazard, as well as danger of injury to the installation and to 30 the equipment served thereby, through the imposition thereon of over-potentials at low frequency. There is also danger of injury to the line and its equipment through the imposition of high frequency potentials 35 thereon. While it is common to provide such circuits with lightning arresters to protect them against high frequency discharges, these devices are not adapted for the discharge of over-potentials at normal 40 frequency, and as a result they are commonly destroyed at the very moment when they are most needed.

45 The present invention provides a protective installation which, first, is extremely sensitive to high frequency current and readily drains the line of bound charges, sneak currents, impulses, etc., all having the characteristics of high frequency but low voltage, while, second, it possesses sufficient 50 capacity to carry and drain the line of over-potentials at low frequency, such as result, for instance, from the falling of a

power line on the conductors of the low voltage circuit.

While an installation embodying this 55 underlying thought may be effected in various ways, I have illustrated a simple and efficient construction which comprises a liquid insulated gap arranged in a ground line and adapted to drain the circuit of 60 over-potentials at low frequency, together with an associated vacuum gap arranged in a shunt around the first-mentioned gap, 65 and serving to drain the line of high frequency potentials.

Such an installation is indicated in Fig. 1, in which the high voltage power line 3 is stepped down by the transformer 4 to the low voltage distribution line 5 in which current utilizing equipment forming the 70 load 6 is arranged. Across the low voltage line 5 are connections 7 and 8 leading to the protective ground line 9, but separated therefrom by an oil gap 10 and a vacuum 75 gap 11 arranged in parallel, the ground terminals of the two gaps being the same, or connected together by a bridge conductor 12. Fuses 13, or other suitable protective equipment, may be arranged in the power line 3.

In the larger scale drawing of Fig. 2, the 80 leads 7 and 8 are connected to terminal bars 14 and 15, which project downward into the tank 16 and enter an insulating fluid 17, such as oil, with which the tank is suitably 85 filled. At the lower end of the terminal rods are electrode terminals 18 and 19, each spaced a slight distance from the submerged 90 ground electrode 20 to which the ground line 9 is connected. The terminals 18 and 19 are preferably of metal of low melting 95 point, such as bismuth, or other suitable material that fuses at relatively low temperature.

The oil gap is shunted by leads 21 and 22 100 extending from the line terminals 14 and 15 to the electrodes 23 and 24, spaced from the ground terminal 25 of the vacuum tube 26, which is connected by the bridge 12 to the ground terminal 20 of the oil gap.

A vacuum gap of the present character is an ideal protector for high frequency impulse or potentials of steep wave front, the partial vacuum being a fair conductor for potentials of these high frequencies. There-

fore high frequency impulses due to lightning discharges, etc., induced on the distribution line 5, are readily drained across the gap of the vacuum tube 26 to the ground line 9.

On the other hand, the oil or other medium of high resistance to impulse voltages at low frequency does not readily permit the passage of high frequency currents to the ground terminal 20. The insulating character of oils and certain other soft insulations, is remarkably higher with respect to high frequency current than with respect to low frequency current. For instance, one inch of oil is readily punctured by a low frequency spark of a few inches, whereas the same one inch of oil will withstand successfully a 50 inch high frequency spark equivalent. The spacing of the terminals 18 and 19 from the ground terminal 20 may therefore be so predetermined that the oil will break down when a low frequency current in line 5 reaches a dangerous potential, while preventing the flow of low voltage high frequency current.

Therefore, the vacuum gap drains the line of potentials of high frequency, or steep wave front, character, but of relatively small voltage, and prevents the submerged oil gap from operating under these conditions. However, the oil gap will break down readily when heavy voltage is imposed on the low voltage circuit, and immediately drains the line of the excess potential. Inasmuch as the discharge of the low frequency, over-potential results in the generation of heat at the gap, this incident to a discharge is utilized to fuse the electrodes 18, 19 and 20, or certain thereof, which are of low melting point. The melting of the terminals causes a short circuit of the line 5, which will have the immediate effect of blowing the fuses 13 in the power line 3, and thus prevent injury to the transformer 4.

The underlying thought of the invention is thus the combination of the two line draining connections, viz, one of extreme sensitiveness to high frequency impulses, and the other of sufficient sensitiveness to low frequency to protect the line against over-potentials, but which is repellent to currents of high frequency and causes the latter to drain off through the agency provided for that purpose. Since this thought is susceptible of embodiment in various forms of apparatus, I do not limit my invention to the particular construction shown, but claim—

1. In a protective ground connection for an electric circuit, a gap sensitively responsive only to low frequency over-potentials and comprising readily fusible electrode means serving by fusion on discharge across the gap to form a continuous metallic path to ground, a shunt across the gap, and in

said shunt a gap sensitively responsive only to high frequency potentials.

2. In a protective ground connection for an electric circuit, gap terminals spaced by an insulating liquid to render said gap sensitive only to low frequency over-potentials, in combination with a shunt across the gap terminals, and in said shunt a gap having terminals spaced by a vacuum to render the gap sensitive only to high frequency potentials. 70 75

3. In a protective ground connection for an electric circuit, a gap sensitively responsive only to low frequency over-potentials and having relative closely spaced terminals and a liquid insulator interposed between the same, in combination with a shunt across said gap, and in said shunt a gap sensitively responsive only to high frequency potentials and having terminals spaced relatively far apart in a vacuum. 80 85

4. In a protective ground connection for an electric circuit, gap terminals spaced by an insulating liquid to render said gap sensitive only to low frequency over-potentials, and means at the gap for short circuiting the line on heavy potential discharge across the gap, in combination with a shunt across the gap terminals, and in said shunt a gap having terminals spaced by a vacuum to render the gap sensitive only to high frequency potentials. 90 95

5. In a protective ground connection for an electric circuit, gap terminals spaced by an insulating liquid to render said gap sensitive only to low frequency over-potentials, certain of said terminals being of low-fusing-point and being so spaced that on fusion a conducting bridge is formed which short-circuits the line. 100 105

6. For use in a protective ground connection, a pair of terminals adapted to be connected across the line, a terminal adapted to be connected to ground, and in parallel between the line terminals and the ground terminal, two gap arrangements, one sensitive only to high frequency potentials, and the other sensitive only to low frequency over-potentials and comprising a grounded electrode, and spaced therefrom a pair of electrodes connected respectively to the line terminals, certain of said electrodes being of metal of low melting point, serving by fusion on the flow of current between the grounded electrode and either of the terminal electrodes to establish a direct metallic ground connection which short circuits the gap sensitive to low frequency over-potentials. 110 115 120

7. For use in a protective ground connection, a pair of terminals adapted to be connected across the line, a terminal adapted to be connected to ground, and in parallel between the line terminals and the ground terminal, two gap arrangements, one sensi- 125 130

tive only to high frequency potentials, and the other sensitive only to low frequency over-potentials, the electrodes of the latter serving by fusion to short circuit the gap on heavy discharge across the gap.

8. In a circuit protecting installation, a ground terminal, and spaced therefrom a pair of terminals connected across the line, an insulating liquid interposed between the

line terminals and the ground terminal, certain of said terminals being of low fusing point and serving on fusion by discharge across the gap, to short-circuit and ground the line.

In testimony whereof I have signed my name to this specification.

CHARLES E. BENNETT.
